UNITED STATES PATENT OFFICE

JAMES C. MASEK, OF IRWIN, PENNSYLVANIA, ASSIGNOR TO WESTINGHOUSE ELECTRIC & MANUFACTURING COMPANY, A CORPORATION OF PENNSYLVANIA

THEATER SWITCHBOARD APPARATUS

Application filed November 2, 1927. Serial No. 230,522.

My invention relates to theater-switchboard apparatus and particularly to switchboard apparatus of the multi-scene, pre-set, variable-lighting type wherein the lighting effects for a plurality of scenes may be pre-selected and selectively operated.

In my copending application, Serial No. 131,303, filed August 24, 1926, I have disclosed theater-switchboard apparatus of the multi-scene, pre-set, variable-lighting type, in which rotary drums are employed for controlling the lighting circuits, the drums being mounted upon a drawer frame that is inserted in openings in a switchboard panel. The drums are mounted with their axes normal to the front face of the panel.

It is an object of my invention to provide a theater-switchboard apparatus that functions somewhat similar to the apparatus disclosed in the above-noted application wherein a rotary drum is mounted upon a drawer frame, with its axis of rotation parallel with the front face of the panel and wherein the edge of the drum, which carries the adjusting device, extends through an opening in the switchboard panel or through an opening in the panel associated with the drawer upon which the drum is mounted. By reason of this arrangement, lateral space is conserved, thus enabling the placing of a large number of control units upon a relatively short switchboard.

A further object of my invention is to provide a theater-switchboard-control apparatus, having the above-noted characteristics, wherein the space economy is effected by a simplification of construction.

A further object of my invention is to provide a theater-switchboard-control apparatus wherein a plurality of lighting circuits may be pre-set to produce pre-selected lighting effects and wherein any desired lighting effect may be produced without disturbing the arrangement of the pre-set apparatus.

These and other objects, that will be made apparent throughout a further description of my invention, are attained by means of the apparatus hereinafter described and illustrated in the accompanying drawings, where-

Figure 1 is a partial top-plan view and partial horizontal section of the apparatus embodying features of my invention.

Fig. 2 is a side-elevational view of the apparatus shown in Fig. 1, a supporting bracket being removed.

Fig. 3 is a side-elevational view of the apparatus viewed from the side opposite that shown in Fig. 2.

Fig. 4 is an elevational view of the inner side of a supporting bracket looking outward from the line IV-IV of Fig. 1.

Fig. 5 is a diagrammatic elevational view of fragments of the apparatus shown in Figs. 1, 2 and 4.

Fig. 6 is a front elevation of a fragment of a switchboard assembly embodying the features of my invention, and

Fig. 7 is a diagrammatic view, in perspective, of the apparatus illustrating the wiring connections for a lighting circuit.

Referring to the drawings, the switchboard structure shown in Fig. 3 is a fabricated metal frame structure 7 having vertical supports 8 and horizontal supports 9 upon which metal drawer frames 11 may be mounted in side-by-side relation, the space between supports 9 being closed by sheet-metal panels 12 that are provided with openings 13 through which the circuit-controlling mechanism is accessible, for the purpose of adjustment.

Each metal drawer frame 11 carries the control apparatus for an individual circuit, and it will be understood that, when the drawer frame is in operative position, all necessary circuit connections are made with the circuit conductors in the manner disclosed in the above-noted copending application. The control units are interchangeable and, in the event of failure of a part thereof, a similar control unit may be put in its place without necessitating serious interruption of the lighting service.

Each control unit is provided with a control rheostat 14, (Fig. 2), the rheostat being mounted upon a part of the drawer frame 11. The rheostat controls the direct-current control circuit of a reactor 10 (Fig. 7), that serves to vary the voltage of the lighting circuit in response to variations in the re-

sistance of the rheostat. The rheostat is relatively small and requires very little energy to operate it.

Each control unit is provided with a rotary drum 15 that is mounted for rotation upon a shaft 16, carried by the drawer frame 11. The periphery of the drum is provided with spur-gear teeth 17 that mesh with the pinion 18 mounted upon a rotary shaft 19 that extends from one end of the switchboard to the other end, in a plane parallel to the front face of the switchboard, the shaft 19 being driven by a motor 21 that may be remotely controlled in the manner disclosed in my co-pending application, Serial No. 230,521, filed November 12, 1927.

The drum 15, (Figs. 1 and 2) is provided with a web 22 to support an adjustable annular cam 23 comprising a plurality of interchangeable links 24 that are pivoted to one another by means of pins 25, each of which is mounted upon an adjustable bracket 26 having individual adjustability toward and away from the web 22, that is, in the direction of the axis of the drum.

Each bracket 26 is provided with an integral shaft 27 that is slidably mounted within a bore 28 in the web 22, and the shaft is provided with a helical peripheral groove 29, the purpose of which will hereinafter appear.

The cam brackets 26 are adjusted to desired positions, within the limit of movement thereof, by means of thumbwheels 31 that are knurled at their edges to facilitate a turning movement of the screw by means of the thumb and finger. The thumb-wheels are rotatably mounted upon the shaft 27 of the brackets 26 and are provided with pins 32 that engage the helical slots 29. Longitudinal movement of the thumb-wheels is prevented by the web 22 on one side and an annular flanged drum 33 that constitutes a part of the drum 15 and is attached to the web 22. The drum 33 carries guide pins 34 which extend through perforations 35 in the bracket 26. Pins 34 serve to prevent rotation of the bracket and also serve as guides for the brackets.

By turning the thumb-wheels 31, the shafts 27 are displaced longitudinally, and the positions of the cam links 23 varied, the positions thereof determining the position of the brush arm 36 of the rheostat 14 and, consequently, the voltage of the lighting circuit. The thumb-wheels are yieldingly retained in definite positions by means of spring pressed balls 20 that engage spherical depressions 20^a in the side faces of the wheels, as shown in Fig. 1.

The operating connection between the adjustable cam 23 and the rheostat 14 comprises a rotary shaft 37 that is mounted for rotation in a bracket 38 which is secured to the drawer frame 11. The front or left end of the shaft is provided with a follower crank

arm 39 having a roller 30 journalled thereon, which engages the cam links 24 and imparts rotary movement to the shaft 37 when the drum 15 is rotated. The follower cam is yieldingly pressed into operative relation to the cam by means of a spring 50 that is wound upon the hub of the clutch 40 and secured at its respective ends to the clutch and the frame 11.

The clutch member 40 is provided with a pinion 41, and is rotatably mounted upon the shaft 37, the pinion 41 meshing with the toothed-gear rack 42, having teeth 42' on two adjacent sides. The rack 42 is mounted for vertical movement adjacent to one of the brackets 38, and the teeth of one face thereof, mesh with a gear-segment 43 that is pivoted for rotation about a pin 44 mounted on the drawer frame 11. The gear segment is provided with an operating lever 45, whereby the rack 42 may be operated manually to impart rotary movement to the shaft 37, when desired.

The gear-segment 43 is provided also with a lever arm 46 to which a connecting rod 47 is pivoted, the rod 47 being pivotally connected to a connecting rod 48 that is attached to a rack 49 which meshes with a pinion 51 connected to the rheostat brush arm 36. A movement of the crank arm 46 imparts rotary movement to the brush arm 36 and causes variations of the resistance in the control circuit.

By reason of the apparatus described, it will be apparent that, as the drum 15 is rotated counter-clockwise, (Fig. 2) the roller 30, moving over the angularly disposed cam links 24, imparts movement to the gear-segment 43 and, consequently, to the brush arm 36 of the rheostat 14. It will be understood that, in the case of a ten-scene switchboard, twenty links 24 are provided, that is, two for each scene. One of the links determines the degree of movement of the rheostat brush arm 36 during movement of the drum 15 through one-twentieth of a revolution or the movement of the drum during a particular scene. The other link assigned to a scene is provided for causing the rheostat brush arm 36 to be moved to the position it should occupy at the beginning of the next succeeding scene. Hereinafter, the first mentioned link will be referred to as the "scene" link and the other link as the "change" link.

When the apparatus is being set up for producing a selected lighting effect for a scene, it is desirable that the operator be enabled to manipulate the rheostat 14 manually in order to determine the degree of illumination that should be used at a predetermined time or during a selected scene. In order to permit of operation of the rheostat arm, it is necessary to disengage the pinion 41 and the shaft 37. The clutch member 40 is provided with a notch 52 of V-shape which

receives a correspondingly shaped clutch block 53 that is carried by a clutch collar 54 that is splined to the shaft 37. A clutch yoke 55 partially surrounds the collar 54 and is provided with pins 56 which engage the annular groove 57 in the clutch collar 54. The yoke is attached to an operating arm 58 that is slidably connected to the arm 45 of the gear-segment 43, the arms 58 and 45 having a slot-and-pin connection, the pins 59 in the arm 58 being adapted to slide in slots 60 in the arm 45, as indicated in Fig. 4.

In order to disengage the clutch connecting the pinion 41 and the shaft 37, the arm 58 is pulled outwardly, thus withdrawing the clutch block 53 a sufficient distance from the clutch member 40 to permit of rotary movement of the pinion 41 without effecting movement of the shaft 37. The rheostat brush 36 may then be manually operated through the medium of the arm 45, independently of the shaft 37 that is actuated by the cam 23.

It is an object of my invention to provide a control apparatus for theater-lighting circuits wherein the illumination may be turned on or off at predetermined times during a scene and wherein the intensity of the illumination may be varied to any predetermined degree as the scene progresses and wherein the lighting effect of one scene may be retained in a predetermined state while the apparatus is being adjusted to a position in which it will effect the lighting for any selected scene or lighting effect. To accomplish the turning off and on of a lighting circuit at predetermined intervals, a normally-open control switch 61 (Figs. 3 and 7) and a normally-closed control switch 62 are provided, which are mounted upon the drawer frame 11.

The switch 61 comprises a stationary contact 63 and a contact arm 64 pivotally mounted upon a pin 65, the outer end of the arm being provided with a pivoted roller 66. The switch arm 64 is normally retained in open position by means of a spring 67 that is disposed between the arm 64 and a fixed lug 68. The normally closed switch 62 is similar in construction to the switch 61 except that the spring 67 serves to normally retain the switch in closed position, as indicated in Fig. 3.

The switches are operated by means of fingers 69 and 71 that are mounted upon the ends of square studs 72 and 73, respectively. The studs are provided with reduced threaded extensions 74 that extend outwardly through slots 75 in the cylindrical face of the drum 15. The threaded portions 74 are provided with pins 76 which fit within notches 77 provided in knurled adjusting knobs 78 that are slidably mounted on the threaded portion 74 of the studs 72 and 73. The knobs 78 are retained in adjusting positions by threaded thumb nuts 79. By loosening the thumb nuts

79, the studs 72 and 73 are loosened with respect to the drum 15, and the studs may be moved along the slots 75 to any desired position. It will be understood that a pair of studs 72 and 73 are provided for each scene that is to be pre-set.

The rollers 66 of the switches 61 and 62 are offset with respect to one another, as indicated in Fig. 3, and the fingers 69 and 71 of the studs 72 and 73 are eccentric to the axis of the studs. Each stud may be rotated about its axis by first loosening the thumb nuts 79 and turning the knobs 78. Thus, the finger 69 or the finger 71 of the studs may be made to engage either one of the switches 61 and 62, depending upon the position of the fingers that engage the rollers thereof.

As indicated in Fig. 3, the finger 71 is holding the normally-closed switch 62 open, and the finger 69 is about to close the normally-open switch. By adjusting the studs 72 and 73 in the slots 75 and by disposing the fingers in the proper relation to the switches 61 and 62, it is possible, if the lighting circuit is closed at the beginning of a scene, to open the lighting circuit at a predetermined time during the scene and to again close it at a predetermined time. In the event that the lighting circuit is open at the beginning of a scene, the circuit may be closed at any predetermined time during the scene and opened subsequently at a predetermined time.

The studs 72 and 73 are retained in their yieldingly adjustable positions by means of a metal spring ring 81 that is yieldingly pressed into engagement with the flat sides of the studs by means of springs 82 mounted on pins 83 and secured to the web 22 of the drum 15. The spring ring serves to retain the studs in proper adjusted positions while the thumb nuts 79 are being tightened and also to prevent displacement of the studs. By turning the studs through 90°, the fingers 69 and 71 may be so positioned that they will not engage and operate the switches 61 and 62, should such operation be desired. It will be understood that the knobs 78 are provided with markings that indicate the relative position of the fingers 69 and 71.

In the apparatus disclosed in my copending application, Serial No. 131,303, the intensity of illumination is maintained constant, when desired, by temporarily arresting movement of a drum which carries the adjustable cam, the driven drum, however, continuing to rotate. Adjustable means are provided by which the movement of the inner drum carrying the adjustable cam may be arrested and started at predetermined times during the scene.

In the present apparatus the intensity of illumination is maintained constant at a predetermined time by disengaging the clutch 40 from the shaft 37. The voltage of the cir-

cuit will, therefore, be maintained constant because the rheostat brush arm 36 will not be affected by the movement of the crank arm 39. When the clutch is re-engaged, the 5 crank arm 39 will move the rheostat arm to a position determined by the adjustable cam.

The clutch is disengaged and re-engaged at predetermined times by means of apparatus disclosed in Figs. 1, 2, 4 and 7. A sliding plate 85 is mounted upon guide pins 86 that are secured to the frame 11, the plate being provided with an extension 84 that is pivotally connected to the clutch yoke 55. The 10 plate is adapted to be reciprocated in a horizontal plane by means of a pair of parallel levers 87 and 88 that are mounted on pivot shafts 89 and 91, respectively, which are secured to the frame 11. Adjustable studs 92 and 93, similar to the studs 73, are mounted 15 for movement in slots 94 in the periphery of the drum 15.

The studs severally comprise a square shaft having a threaded portion 95 upon which thumb-nuts 96 and 97 are mounted, the nuts 20 being similar to those mounted on the studs 73 and being for the same purpose, that is, for retaining the studs in adjusted position in the slots 94. The square portions of the studs 92 and 93 are provided with pins 90 and 98, respectively (Fig. 5) and are adapted 25 to engage rollers 99 and 101 on the free ends of the levers 87 and 88, respectively, as the drum 15 carries the studs past the levers 87 and 88.

30 The lower ends of the levers 87 and 88 are provided with slots 102 that engage pins 103 on the sliding plate 85. When the parts are 35 in the positions shown in Fig. 7, the pin 90 on the stud 92 will first engage the roller 99 and cause the lever to rotate counterclockwise and move the sliding plate to the right or outwardly, thus causing the clutch to be 40 disengaged. Further movement of the drum 15 will cause the pin 98 on the stud 93 to 45 engage the left side of the roller 101 and cause the lever 88 to be moved in a clockwise direction, thus causing the clutch to be re-engaged.

It will be noted that the studs 92 and 93 50 are provided with pins 104 and 105, respectively, which will operate the levers 88 and 87, respectively, when the studs are turned to 90° from the positions shown in Fig. 5. By reason of this arrangement of the pins, 55 either stud may be positioned to actuate either of the levers 87 and 88. If the clutch is opened at the beginning of a scene, it may be closed at a predetermined time and re-opened at a predetermined time during the 60 scene. If the clutch is opened at the beginning of a scene, it may be subsequently closed at a predetermined time and again opened at a predetermined time during the scene.

It is frequently desirable, especially for 65 the purpose of rehearsals or for the purpose

of certain types of performances, to shift from the setting for producing a preset lighting effect to another preselected setting, while retaining the first effect. In the event that it is desired to change from the illumination for scene 1, for example, to the illumination effect pre-set for scene 5, it is necessary to prevent the apparatus from effecting any change in the circuit condition. For example, the apparatus which has been set for the intermediate scenes 2, 3, and 4 should, in no way, effect the condition of the lighting circuit. To accomplish this, a normally open switch 106, (Figs. 4 and 7) and a normally closed switch 107 (Figs. 4 and 7) are provided in the control circuit to serve to maintain the circuit condition prevailing at the time the clutch member 40 is disengaged from the shaft 37.

The switches 106 and 107 are pivoted to a plate 108 secured to the frame 11 and comprise switch arms 109 and 111, respectively, that are pivoted to shafts 112 and 113, respectively. The shafts are secured to the plate 108. Rollers 114 and 115 on the switch arms normally engage the lower edge of the sliding plate 85 that is provided with cams 110 and 117. When the plate is moved outwardly in response to disengagement of the clutch 40, the rollers 114 and 115 are depressed, causing the normally open switch 106 to be closed and the normally closed switch 107 to be opened.

At such time, the switches 61 and 62 are rendered electrically inoperative to influence the coil of the relay 116.

It will be understood that, with the exception of the addition of switches 106 and 107, each lighting circuit is substantially the same as that described in the said copending application, Serial No. 131,303, wherein the lamps 120 of the electrical circuit are supplied with current from alternating current feed conductors 118 and 119, the current passing through the outside coils of the reactor 10 and through contacts 121 and 122 of the relay 116. The voltage of the lighting circuit is controlled by current from direct-current feed conductors 123 and 124, the current passing through the brush arm 36 and resistance element of the rheostat 14 and through a coil 125 that surrounds the center leg of the reactor 10.

The relay 116 is controlled by the normally open switch 61 and the normally closed switch 62 that are connected in the circuit of the coil of the relay 116, which is supplied with energy from the direct-current feed conductors 123 and 124. The circuit connections of the switches 61 and 62 are such that, when the normally open switch 61 is closed momentarily, by the contact fingers 69, the relay 116 is energized and is held in energized or closed condition by current flowing through the coil thereof and the normally closed

switch 62. The relay is subsequently opened by momentarily opening the normally closed switch 62 by engagement therewith of the contact fingers 71 adjustably secured to the drum 15. By reason of the control switches 61 and 62, the lighting circuit may be energized and de-energized at predetermined times during the scene, depending upon the adjustment of the fingers 69 and 71.

10 The normally open switch 106 and the normally closed switch 107 are so connected to the switches 61 and 62 that, when their positions are reversed, by reason of the disengagement of the clutch 40 from the shaft 37, and movement of the plate 85, they render the switches 61 and 62 electrically inoperative to influence the coil of the relay 116, the switch 106 being connected in parallel with the switch 62, and the switch 107 being connected in series with the switch 61.

The circuit which would normally be completed by closing the switch 61, is interrupted at the switch 107 and, therefore, the operation of the switch 61 does not effect the control circuit of the relay 116. Since the normally open switch 106 is connected in parallel with the normally closed switch 62 and since, at this time, the switch 106 is closed, the switch 62 may be moved to open position 20 without effecting any change in the control circuit of the relay 116.

If the control circuit is closed through the relay 116 at the time the clutch member is disengaged, it will remain closed, regardless 35 of the operation of the switch 62, by the control finger 71 on the drum 15. If the circuit is open, it will remain open, regardless of the operation of the normally open switch 61, by the control finger 69.

40 By reason of the switchboard apparatus above described, the switchboard may be pre-arranged to produce different and variable lighting effects for a plurality of scenes, and to cause any circuit to be energized to any 45 degree within the voltage limits at any predetermined time and for any predetermined length of time during a scene, and it is possible to follow one lighting effect with any selected pre-set lighting effect without 50 effecting a change of the circuit condition during the interval in which the apparatus is actuated to prepare it for the production of the selected effect.

The pinions 18 on the master drive shaft 55 19 are connected thereto by means of clutches 126 which may be operated from the front face of the panel drawer containing each control unit and, by disengaging the clutch 126, the drums 15 may be rotated independently 60 of one another for the purpose of individually manipulating the control apparatus for an individual circuit. This is desirable during rehearsals or at the time experiments are being conducted to determine a desired lighting effect.

The drawer unit may be individually withdrawn from the switchboard structure for the purpose of inspection and repair without disturbing the neighboring units, the circuit connections between the conductors on the switchboard structure and the apparatus on the drawer being of a disconnecting type, such as is disclosed in the said co-pending application, Serial No. 131,303.

70 While I have illustrated but one embodiment of my invention, it will be apparent to those skilled in the art that various changes, modifications, substitutions, additions and omissions may be made in the apparatus illustrated without departing from the spirit and 75 scope of my invention as set forth in the appended claims.

I claim as my invention:

1. Current-control mechanism comprising 80 a rotary cylindrical drum, a rheostat, means on the drum for effecting operation of the rheostat when the drum is rotated and means accessible from the outer cylindrical face of the drum for adjusting the said means.

2. Current-control mechanism comprising 85 a rotary cylindrical drum, a current-controlling device, means on the drum for effecting operation of the said device when the drum is rotated and means accessible from the outer cylindrical face of the drum for adjusting 90 the said means.

3. Current-control mechanism comprising 95 a switchboard having an opening therein, a cylindrical drum mounted thereon for rotation and having its cylindrical face extending through the said opening, a current-controlling device, means on the drum for effecting operation of the device when the drum is rotated, and means accessible from the outer cylindrical face of the drum and 100 through the said opening for adjusting the 105 said means.

4. Current-controlling mechanism comprising 110 a relay for controlling a circuit, a pair of momentary contact switches for controlling the relay, a continuously movable member for actuating the contact switches at predetermined intervals, a current-controlling device, a releasable connection between the said device and the movable member and 115 means for actuating the releasable member, and means associated with the releasable member for rendering the said contact switches inoperative when the said connection is in a predetermined position.

5. The combination with a plurality of 120 current-controlling devices and a continuously moving member, of pre-settable means having a part continuously operating and actuated by the said member for effecting operation of the said devices at predetermined intervals while the member is moving, and means for selectively rendering the said means ineffective to effect operation of a selected device.

6. The combination with a current-controlling device and a continuously moving member, of a pre-settable means having a part continuously operating and actuated by
5 the said member for effecting operation of the said device at predetermined intervals, a clutch connecting the device and the said means, and means for actuating the clutch to render the said means ineffective to effect operation of the said device.

10 7. Control apparatus comprising a plurality of current-responsive current-controlling devices, control switches for each of the devices, pre-settable means for actuating the switches at predetermined times and in predetermined sequence and means for selectively rendering the said switches, although operated, ineffective to affect a selected device.

15 8. Control apparatus comprising a plurality of current-responsive current-controlling devices, control switches for the devices, pre-settable means for actuating the switches at predetermined times and in predetermined sequence and switches for selectively rendering the said switches, although operated, ineffective to affect a selected device.

20 9. Control apparatus comprising an electric circuit, a current-responsive controlling device therefor, control switches for the device, pre-settable means for actuating the switches at predetermined times and in predetermined sequence, pre-settable means for controlling the energy of the circuit, means for arresting operation of the energy-controlling means at predetermined times, and means actuated by the last said means for rendering the first said switches ineffective to affect the said device.

25 10. In testimony whereof, I have hereunto subscribed my name this 7th day of October 1927.

JAMES C. MASEK.
